UNITED STATES PATENT OFFICE

1,954,827

LUBRICATING DEVICE

Morris Newmark and Elias Moss, New York, N. Y.

Application February 11, 1932, Serial No. 592,305

6 Claims. (CL 285—143)

This invention relates to lubricating devices, and more particularly to the class of such devices adapted to supply grease under pressure to surfaces requiring lubrication.

- 5 One of the objects of the invention is to produce a device of this character, the delivery end of which may be quickly attached to and detached from a nipple or lubricant receiving receptacle.
- 10 Another object of the invention is to provide a device of the nature referred to that will make leak-proof contact with the lubricant receiving receptacle.

15 A further object of the invention is to provide a device of this nature comprising an outer shell adapted to be brought into coupling engagement with a lubricant receiving receptacle and a hollow stem or plunger in communication at one end thereof with the pressure lubricator, and at the 20 opposite end with pilot means adapted to enter the lubricant receiving receptacle and make leak-proof contact therewith.

25 A still further object of the invention is to provide the said shell and plunger with screw thread means for quickly bringing the said plunger into operative engagement with the lubricant receiving receptacle, and releasably locking the said parts together.

30 Another object is to produce a device of the character described in which the maximum simplicity of construction and operation is secured.

35 Other objects and advantages will appear as the nature of the improvements is better understood, the invention consisting substantially in the novel arrangement and co-relation of parts herein fully described, and illustrated in the accompanying drawing, wherein similar reference characters are used to describe corresponding parts throughout the several views, and then 40 finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

45 The inventive idea involved is capable of receiving a variety of mechanical expressions, one of which, for the purpose of illustration, is shown in the accompanying drawing, in which—

50 Figure 1 is a view in elevation of a preferred form of our improved lubricating device in position ready to be attached to the lubricating re-

ceptacle leading to the surface to be lubricated.

Figure 2 is a vertical section thereof taken on line 2—2 Figure 1 showing the device in engagement with the lubricator receiving receptacle.

Figure 3 is a bottom plan view thereof looking up towards the bottom end of the device.

Figure 4 is a fragmental sectional view of a modified form of the invention, and

Figure 5 is a perspective view of the pilot portion of the said modified form.

Referring now to the drawing in detail 10 indicates a nozzle comprising an outer shell or barrel 11 having preferably an internal quadruple thread 12 adapted to receive a similarly threaded portion 13 of an internal hollow stem or plunger 14. The said stem is provided at its upper end with an internally screw threaded opening 15 into which is threaded the lower end of a suitable tube or conduit 16 leading from a pressure lubricator 17 indicated in dot and dash lines Figure 1.

The bottom of the shell or barrel 11 is provided with a cut out 18 so that the shell may be adapted to be slid into engagement with a lubricator receiving receptacle 20 which is screwed into an opening 21 in a bearing 22 and in communication with the part to be lubricated. The said receptacle is provided with a cylindrical body portion 23 an enlarged disc portion 24 and a nipple 25, the disc 24 being provided with an annular groove 24—a in its upper surface.

80 The lower portion 26 of the plunger 14 is somewhat smaller in diameter than the main body portion thereof and terminates in a recessed end 27 forming an external rim or flange 28 and an inner central seat or pilot 29 provided with an opening 30 in communication with a bore 31 opening into the threaded hole 15. A cupped washer 33 is fitted into the recess 27 and when the plunger is in lowered position the said washer makes a leak proof joint with the nipple 25, and the flange 28 which enters the annular groove 24—a provides additional means for making the joint leak proof.

85 To attach the device to the receptacle 20 the shell 11 is slid over same and by slight rotary movement of the said shell the plunger 14 is rapidly brought from the normal dot and dash position (Figure 2) to the full line position and into operative locking engagement with the receptacle. This rapid action is due to the multiple threads 12 and 13. The downward movement of the plunger 14 causes the seat 29 to enter the receptacle 20 and the flange 28 to enter the groove 24—a to provide a grease tight joint when the 90 95 100 105 110

lubricating pressure device 17 is operated to force lubricant through the central bores 31 and 30 into the lubricator receptacle. The teat 29 also forces the spring pressed ball valve 36 away from its seat to permit the flow of the lubricant into the receptacle.

In Figures 4 and 5 we have shown a modified form of our invention wherein the plunger 14 is provided with a lower threaded extension 40 having a reduced bore 41 into which extends the shank 42 of a pilot 43. The said pilot 43 has an end recess 44 similar to the recess 27 providing a central teat 45 and an outer flange 46 between which there is inserted a washer 47 to contact with the nipple 25 and form a leak-proof joint when the device is in operation. A tubular casing 48 is screw threaded secured to the plunger extension 40 and maintains the pilot in place. An offset opening 49 in the said pilot permits grease to be forced therethrough to the receptacle 20. If desired the casing 48 may be provided with a flange 50 to enter the groove 24—a of the disc 24. The shank 42 of the pilot 43 may be flattened as at 51 so that the grease may easily reach the opening 49. In this form of our invention the pressure of the grease acting upon the shoulder 52 will tend to hold the pilot tightly against the receptacle 20 to form a leak proof joint.

From the foregoing it will be seen that we have provided a quick acting leak proof nozzle for a lubricating device, adapted to be readily coupled with or secured to a lubricator receptacle for automobiles and the like.

Having described our invention what we claim as new and desire to secure by Letters Patent is:

1. A nozzle adapted to be secured to a pressure lubricating device, comprising a barrel having an internal multiple thread, a screw threaded plunger rotatably mounted therein and having a bore in communication with the pressure device, a grease receptacle having a central bore and an annular groove therein, and an end on the plunger adapted to enter the said groove when the said plunger is rotated to bring the bore therein into operative communication with the central bore.

2. A nozzle adapted to be secured to a pressure lubricating device, comprising a barrel having an internal multiple thread, a multiple screw threaded plunger rotatably mounted therein and having a bore in communication with the pressure device, a grease receptacle having a central bore and an annular groove therein, and an end on the plunger adapted to enter the said central bore and groove.

3. A nozzle adapted to be secured to a pressure

lubricating device and lubricator receptacle, comprising a barrel, a plunger having a bore in communication with the pressure device and lubricator receptacle, means on the said barrel and plunger to produce a relative sliding and rotating movement between the said parts, a grease receptacle having a central bore and annular groove therein, and an end on the plunger adapted to enter the said groove when the bore in the plunger is brought into direct communication with the central bore in the receptacle.

4. A nozzle adapted to be secured to a pressure lubricating device, comprising a barrel, a plunger having a bore extending the entire length thereof and in communication at one end with the pressure device, screw thread means on the said barrel and plunger to produce a relative sliding and rotating movement between the said parts, a grease receptacle having a central bore and annularly grooved flange, and an end on the said plunger adapted to enter the said receptacle bore and groove.

5. A nozzle adapted to be secured to a pressure lubricating device, comprising a barrel, a plunger having a bore extending the entire length thereof and in communication at one end with the pressure device, screw thread means on the said barrel and plunger to produce a relative sliding and rotating movement between the said parts, a grease receptacle having a central bore and annularly grooved flange, a pilot at the other end of the plunger bore, the said pilot being provided with a bore in communication with the plunger bore, a teat on the pilot adapted to enter the grease receptacle, a shouldered shell for maintaining the pilot in the plunger, and a flange at the end of the said shell to enter the receptacle groove.

6. A nozzle adapted to be secured to a pressure lubricating device and lubricator receptacle, comprising a barrel having a cutout at the bottom end thereof, a plunger adapted to be shifted longitudinally by rotary motion mounted in the said barrel and having a bore in communication at one end with the pressure device, a perforated pilot operatively mounted at the other end of the said bore, a grease receptacle having a bore in communication with the plunger bore, a disc on the said receptacle for seating and coupling engagement with the barrel cutout, means for maintaining the pilot in the plunger bore, and the end of said plunger constructed for engagement with the said disc to produce a grease tight joint.
